READING GLASS

James N. Burlin, New York, N.Y., and Henry Dreyfuss,
South Pasadena, Calif., assignors to Bausch & Lomb
Incorporated, a corporation of New York

Filed June 6, 1960, Ser. No. 60,854

Term of patent 14 years

(Cl. D57—1)

FIG. 1

FIG. 3

FIG. 1 is a perspective view of a reading glass showing our new design;

FIG. 2 is a top plan view thereof; and

FIG. 3 is an enlarged elevational view thereof taken from the left end of FIG. 1.

We claim:

The ornamental design for a reading glass, substantially as shown.
